(57) **CLAIM**

The ornamental design for a lid with handle for beverage bottle, as shown and described.

DESCRIPTION

FIG. 1 is a perspective view of a lid with handle for beverage bottle, showing my new design;

FIG. 2 is rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof; and,

FIG. 9 is a perspective thereof, showing the mouthpiece in open position.

The broken lines depict portions of the lid with handle for beverage bottle that form no part of the claimed design.
